CLAIM

The ornamental design for a plug assembly, as shown and described.

DESCRIPTION

FIG. 1 is a perspective view showing our new design;

FIG. 2 is a top plan view thereof;

FIG. 3 is a front elevation view thereof;

FIG. 4 is a first side elevation view thereof;

FIG. 5 is a rear elevation view thereof;

FIG. 6 is a second side elevation view thereof; and,

FIG. 7 is a bottom plan view thereof.

The broken lines depict portions of the plug assembly that form no part of the claim.
